(No Model.)

O. B. COLCORD.

GRAIN ELEVATOR FOR HARVESTERS.

No. 277,993.

Patented May 22, 1883.

UNITED STATES PATENT OFFICE.

OTIS B. COLCORD, OF GREENVILLE, ILLINOIS.

GRAIN-ELEVATOR FOR HARVESTERS.

SPECIFICATION forming part of Letters Patent No. 277,993, dated May 22, 1883.

Application filed December 13, 1882. (No model.)

To all whom it may concern:

Be it known that I, OTIS B. COLCORD, a citizen of the United States, residing at Greenville, in the county of Bond and State of Illinois, have invented a new and useful Grain-Elevator, of which the following is a specification, reference being had to the accompanying drawings.

This invention relates to means for elevating grain and the like, and is especially adapted for elevating grain from the platform-canvas or carrier-apron of a harvester to the binder deck or table.

My invention has for its object to provide a simple and efficient mechanism that will effect positive elevation of any and all kinds of grain, that will accommodate itself to these varying kinds and conditions of the grain, that will perform its functions with greater ease and accuracy, and that will secure the grain from waste by falling off or being blown off the elevator.

In self-binding harvesters the elevation of the grain to the binder-table has been heretofore effected by means of an elevating apron or canvas having cross-bars, that travels upwardly and carries the grain over and on top, where it is exposed to the action of the winds, &c. This elevating means is disadvantageous in many other particulars, among which may be mentioned the fact that it does not hold the grain compactly while it is being elevated, so that it is delivered on the binder-table in a diffused and scattered gavel; but in my invention the grain is elevated by the lower or under strand of an endless apron, and is held against guides under the elevating mechanism by elastic teeth, which also carry it upwardly between the said guides and elevator. By this means the grain is held on all sides and kept in compact form until it is delivered on the binder-table and the gavel is bound.

The objects of my invention are attained by means of the mechanism illustrated in the drawings, in which—

Figure 1 is a perspective view illustrating my elevating mechanism adapted for use on a harvester. Fig. 2 is a vertical longitudinal sectional view of the same. Fig. 3 is a transverse sectional view of Fig. 2. Fig. 4 is a detail perspective view of one of the spring-toothed cross-bars.

Referring to the drawings, A designates the frame of the elevator, which is in this instance arranged like the ordinary apron-elevator frame, and consists of side boards, B B, and the inclined bottom C. On the bottom C are secured a number of parallel guiding and supporting ribs or strips, D, on which the grain rests as it is being elevated, and each side board, B, carries chain-pulleys E E at its top and bottom. On both of these pairs of pulleys E E travel chain belts F F, the links of which are provided at suitable intervals with lateral lugs or extensions G G, having perforations H. These lugs G G enter the kerfs I I of the bifurcated ends of the cross-bars J, and the latter are by this means secured on the chain belts F F, a bolt, K, being passed through each bifurcated end I and lug G.

L designates the spring carrier-teeth that are secured on the cross-bars J. These teeth L are arranged in pairs M, that are formed of a single piece of elastic wire, N, comprising a straight central portion, O, which is secured to the cross-bar J by staples P, and has each end coiled round the cross-bar, as at Q, and extended out to form the tooth L. The coils Q admit of additional elastic movement on the part of the teeth, which have their points R bent slightly, as shown. The teeth L travel between the ribs D as the cross-bars are carried by the chain belts F F at the sides of the elevator.

S designates a number of endless bands that are disposed longitudinally and are arranged around the cross-bars J, the function of said bands being to retain the grain down against the ribs D as it is being elevated.

The operation and advantages of my invention are obvious. The two chain belts are driven in the direction shown by the arrows by suitable mechanism connecting them with the drive-wheel. The grain is carried upwardly by the spring-teeth, which pass between the ribs D and the under side of the elevator mechanism, which latter of course moves upwardly, and it is retained from displacement during elevation. The herein-described form of spring-teeth readily adapt themselves to varying sizes and conditions of grain.

I claim as my invention—

As an improvement in grain-elevators, the

combination of the frame A, having inclined bottom C, the parallel guiding and supporting strips D, secured longitudinally on the said bottom, the elevating mechanism having the 5 cross-bars J, carrying spring-teeth L, having the bent points R, that engage the bottom C and travel one between each two of said strips D, and the endless bands or cords S, disposed longitudinally around the bars J, by which

they are supported but not connected to the 10 said bars, as set forth.

In testimony that I claim the foregoing as my own I have hereto affixed my signature in presence of two witnesses.

OTIS B. COLCORD.

Witnesses:

LEMUEL ADAMS,
GEO. W. SMITH.
